UNITED STATES PATENT OFFICE.

HENRY I. WINTERFIELD, OF DANBURY, CONNECTICUT, ASSIGNOR OF ONE-HALF TO ROBERT KERR, OF SAME PLACE.

HAT-RACK FOR HAT-MANUFACTURERS.

SPECIFICATION forming part of Letters Patent No. 376,933, dated January 24, 1888.

Application filed May 16, 1887. Serial No. 238,481. (No model.)

To all whom it may concern:

Be it known that I, HENRY I. WINTERFIELD, a citizen of the United States, residing at Danbury, in the county of Fairfield and State of Connecticut, have invented certain new and useful Improvements in Hat-Racks for Hat-Manufacturers; and I do hereby declare the following to be a full, clear, and exact description of the invention, such as will enable others skilled in the art to which it appertains to make and use the same.

My invention has for its object to provide a device for holding hats which shall be adapted for use under all circumstances, in which a number of hats—for example, a dozen—are to be exhibited or to be moved about from one place to another, and which shall be especially adapted for use in hat-factories, it being necessary to provide racks or frames that will hold a number of hats, in which they may be transported from one portion of the factory to another while undergoing the different steps in the operations of finishing and preparing for the market.

With these ends in view I have devised the simple and novel construction, of which the following description, in connection with the accompanying drawings, is a specification, numbers being used to indicate the several parts.

Figure 1 is a perspective of my improved hat-rack complete; Fig. 2, a section of a portion thereof, showing a hat in position but not clamped; and Fig. 3 is a similar view showing a hat clamped in position.

1 denotes the frame-work of the rack, which may be of any suitable or preferred construction; 2, supporting-bars upon one side of the rack, which are fixed in the frame-work; and 3, supporting-bars on the opposite side of the rack, which are adapted to turn freely in the frame-work. The turning-bars are provided with loops or pins 4 of any suitable shape, and are connected by a suitable strip, 5, which is loosely secured to each rod in substantially the same manner that the connecting-rod is secured to blind-slats. One end of one of the turning-rods passes through the frame-work, and is provided with a crank or handle, 6.

7 denotes longitudinal strips in that side of the frame-work in which the turning-bars are

journaled, one of these strips being placed a short distance above each of the turning-bars, as will be more fully explained.

My improved racks are adapted for use in carrying all sizes, styles, and qualities of hats without the necessity for any adjustment whatever, and may be made of any required size—that is, to carry any desired number of hats.

The rack illustrated in the drawings is designed to carry a dozen hats—that is, four rows of three hats each—the loops being shown as placed far enough apart to accommodate any possible width of brim without the hats coming in contact.

The operation is as follows: The hats are held by cross-bars 2 and 3, resting on both, and when the rack is filled, or the desired number has been placed in position, the crank or handle is given a quarter-turn, which turns one of the loops or pins 4 up into each hat and binds it against one of the side strips 7. In Figs. 1 and 3 the parts are shown in the clamped position. To throw them from this position to the position shown in Fig. 2, it is simply necessary to give crank or handle 6 a quarter-turn inward. As soon as the desired number of hats are placed in position a quarter-turn of the handle back to the position shown in Fig. 1 clamps the hats in position, as clearly shown in Fig. 3. The turning-bars being connected by strip 5, it is made certain that every hat shall be clamped in position, whether the rack is filled or not.

It will of course be understood that the details of construction may be varied to an almost unlimited extent without departing from the spirit of my invention.

I claim—

1. A hat-rack consisting of frame-work, supporting bars in one side thereof and turning-bars in the other side, which are provided with loops or pins adapted to engage the interior of the hats.

2. A hat-rack consisting of frame-work, side bars 2, turning-bars 3, having loops or pins 4, and a strip connecting said turning-bars, whereby a movement of either bar carries the others with it.

3. A hat-rack consisting of frame-work, side bars 2, turning-bars 3, having loops 4, strip 5, connecting the turning-bars, and side bars 7,

in the frame-work just above the turning-bars, against which the hats are clamped by the pins when in use.

4. In a hat-rack, bars 2 and turning-bars 3, 5 having loops or pins 4, in combination with a strip, 5, connecting the turning-bars, side strips 7, against which the hats are clamped by the loops or pins, and a crank or handle adapted to engage one of the turning-bars, 10 whereby all the hats are clamped at once.

5. In a hat-rack, the combination, with bars 2 and side strips 7, of turning-bars 3, having loops 4, whereby the hats are clamped against the side strips.

In testimony whereof I affix my signature in 15 presence of two witnesses.

HENRY I. WINTERFIELD.
